UNITED STATES PATENT OFFICE.

EDWARD E. KLEINSCHMIDT, OF BROOKLYN, NEW YORK, ASSIGNOR, BY MESNE ASSIGNMENTS, TO MORKRUM-KLEINSCHMIDT CORPORATION, OF CHICAGO, ILLINOIS, A CORPORATION OF DELAWARE.

PRINTING TELEGRAPHY.

Application filed October 3, 1921. Serial No. 504,862.

The present invention relates to transmitting mechanism for printing telegraphs employing the Baudot or similar codes and it has for its particular object the production of an apparatus of great simplicity of construction and operation.

It furthermore combines perforated tape controlled automatic signal transmission with means for automatically interrupting the normal operation thereof and interpolating the transmission of auxiliary signals, such as service signals.

It also utilizes a single transmitting contact tongue for transmitting code signal and service signal impulses by means of operating means which are in part only common to both sets of signal impulses.

It finally provides means for insuring perfect contact between the contact tongue and the marking and spacing contact respectively, whereby the chattering of the contacts incident to the reversal of current polarity is successfully eliminated.

Arrangements of this general character are old in the art, as for instance, in the U. S. Patent #1,275,559, but no effective efforts have been made to bring the mechanism to a simple form without decreasing its efficiency. The single transmitting contact shown in the U. S. Patent #1,299,608 has been combined in the present invention with operating mechanism therefor, which is under the double control of the main signalling means, as well as the service signal means. A new tape feeding device is used as well as a new arrangement controlled by the tape for first automatically interrupting and then re-starting the transmitting mechanism, as shown in the U. S. Patent #1,192,171.

One form of construction of the invention is shown in the drawings in which:

Fig. 1 is a front elevation, Fig. 2 a plan view partly in horizontal section thru the main driving gear, Fig. 3 an elevation along the axis of the main driving shaft, Fig. 4 an elevation of the tape feeding mechanism, Fig. 5 a similar view of the interrupting and re-starting mechanism, Fig. 6 a plan view of a portion of the perforated tape and its feeding means, Fig. 7, a detail of the service signal transmitting mechanism and

Fig. 8, an elevation showing the means for insuring perfect contact at the marking and spacing contacts.

The apparatus comprises a frame 10, supporting a base plate 11, provided with a front bearing 12 and a rear bearing 13 for the shaft 14 of the main gear 15 which is in mesh with a driving worm 16, secured to a driving shaft 17, receiving rotary motion from a driving motor 18. The main gear 15 is in contact with a front friction disk 19 and a rear friction disk 20. The shaft 14 carries a plurality of operating cams 21 and a tape feed cam 22. This tape feed cam operates a cam lever 23 provided with a cam shoe 24, riding upon the periphery of the tape feeding cam 22. The end of the cam lever 23 opposite to the cam shoe 24, is pivoted to a pawl arm 25, resiliently held by a retaining spring 26 and carrying a pawl 27, sliding in a pawl guide 28, connected to the pawl arm 25 by means of setting devices 29. The pawl 27 engages a ratchet 30, rotatable on the ratchet shaft 31, carrying the feed wheel 32, the peripheral pins of which are engaging the middle row of perforations of the tape 33. A jockey roller 34 is provided on a lever 35 pivoted on an adjustable bracket 36, for positively locating the jockey roller in the teeth of the ratchet 30. The spring 37 holds the jockey roller 34 in close contact with teeth of the ratchet 30.

The cams 21 secured to the main shaft 14 are adapted to engage a plurality of cam levers 38, all of which are pivoted on a shaft 39 and each resiliently held by a spring 40. The ends of the cam levers 38, opposite the ends engaged by the cams 21, move in a guide comb 41. Each of the cam levers 38 permits to actuate a corresponding operating lever 42, all of which are pivoted on a shaft 43 and resiliently held by helical springs 44.

The selecting pins 45, of which there are five in number, in a system employing the Baudot code, are at one end of pin rods 46, capable of vertical movement caused by cam levers 38. Each of the entire number of operating levers 42 is capable of actuating a common contact lever 47, normally retained by a spring 48 and provided with a contact

tongue 49, adapted to make contact with either a spacing contact 51 or a marking contact 50.

The perforated tape 33 travels under a tape guide plate 52 and controls the movement of the selecting pins 45, as well known in transmission apparatus of this general character. A tape feed stop 53 is manually operated and arranged to depress the pawl 27 and hold the same out of engagement with the ratchet 30, so that for the period of depression of the feed stop, the feed movement of the tape is interrupted.

Fig. 5 illustrates the tape lever 60 consisting of a rod having a rectangular extension 61, normally resting upon the perforated tape 33, before it is fed into the transmitting mechanism. The lever 60 is rotatable on the shaft 62, and is rigidly connected to an arm 63. Pivotedly connected to a bracket on the stationary frame of the apparatus is a latch 64, having at its lower end a pin 65, connected by means of a helical spring 66, to the upper end of the arm 63. In raising the free end of the lever 60 and displacing the arm 63, the spring 66 exerts a pull upon the pin 65 of the latch 64, bringing the latter into the path of rotation of a transmission stop 67, secured to the main shaft 14 and stopping the same. Near the free end of the lever 60 there is a lever guide 68, and resilient means 69 for holding the lever 60 in its extreme uppermost position from which it can be manually displaced to permit the re-starting of the transmission mechanism, by moving the latch 64 out of the path of rotation of the transmission stop 67.

The auxiliary or service signalling mechanism includes a shaft 70 provided at one end with a code wheel 71 and at the opposite end with a driving gear 72. This gear is in mesh with a pinion 73 on the main shaft 14. The pinion 73 is integral with the friction disc 20 of the main gear 15 and the service signalling mechanism is, therefore, operated by the same gear 15 as the main signalling mechanism. The friction disc 19 on the face of the gear 15 opposite to that of friction disc 20, actuates the main signalling mechanism while the friction disc 20 actuates the service signalling mechanism. Inasmuch as the simultaneous transmission of main signals and service signals would naturally result in the jumbling of signals and the formation of unintelligible combinations of current impulses, the transmission of two kinds of signals must take place in succession by means of a following arrangement.

A resilient lever 77 is secured to a shaft 78 which carries an arm 79 having at its upper end a roller 80 and held by a retaining spring 81 toward a disc 85. The arm 79 is provided with a detent 82 for stopping the rotation of the shaft 14 of the main signal

transmitting device and a second detent 83 for stopping the rotation of the shaft 70 of the service signal transmitting device.

Shaft 14 of the main signal transmitting device carries a disc 84, Fig. 7, and shaft 70 of the service signal transmitting device, a similar disc 85. The disc 84 is provided with two diametrically opposite peripheral notches 86 and 87 and the disc 85 with a similar single notch 88.

When the operating handle 89, Fig. 1, is pushed to the right, and, assuming that the main signalling mechanism, including shaft 14, is now in action, the roller 80 rides on the periphery of disc 84 for the time of not more than half a revolution of the shaft 14 whereupon it enters one of the notches 86 or 87.

At this moment, the detent 83, normally resting in the notch 88, on account of the pull of spring 81, is removed from the notch 88 and the second detent 82 is, therefore brought into the path of rotation of the stop arm 67 of the shaft 14. Keeping in mind that the main gear 15 is constantly rotating it will be seen that the friction disc 19 and all parts associated with it, including the operating cams 21 are held at rest by means of the stop arm 67, while the pinion 73, connected to the friction disc 20, is permitted to rotate, causing the rotation of the shaft 70 of the service signalling device and its associated parts.

A lug 74 arranged on the driving gear 72 displaces the bell hammer 75 and operates an audible signal on bell 76, indicating to the sending operator that the normal transmission of signal impulses has been replaced by the transmission of service signal impulses.

The service signal code wheel 71 is provided with cams 90, of such a number and so distributed along the periphery of the code wheel, as to represent any desired series of pre-determined signals, for instance "carriage shift", the letter "J" and the "carriage release". In the event that the signal represented on the code wheel 71 is to be repeated, the operator holds the handle 8 until the bell 76 is struck a second, third or more times, indicating the number of times the code signal has been sent.

The cams 90 of the service code wheel 7 are arranged to actuate the arm 91 of bell crank lever 92, pivoted at 93 and to engage one end of a lever 94, located between the cam levers 38 and having the double function of aiding in the transmission of main signals as well as service signals.

The means for insuring perfect contact at the marking and spacing contacts comprise a cam 95, secured to shaft 14 and rotatable therewith. This cam engages on end of a lever 96, pivoted at 97, the opposite end 98 of which is provided with a pi-

99. The lever 96 is resiliently held by a spring 100. The pin 99 engages a lever 101, pivoted on shaft 97, and having at its free end a knife-edge 102 adapted to engage either side of the beveled end of a resilient member 103, secured to the contact lever 47. A spring 104 is instrumental in causing resilient contact between the co-acting portions of the members 102 and 104.

The teeth of cam 95 are so arranged that the member 102 is disengaged from member 103 at the instant of sending a signal impulse, permitting the contact tongue 49 to make contact with either the spacing or marking contacts 50 and 51, but immediately thereafter holding the contact tongue 49 in tight contact with the contacts and during the duration of the contact successfully preventing the chattering thereof.

One of the most important features of the operation of device shown in Fig. 8 consists in the fact that the position of the teeth on cam 95 in relation to the cams 21, is such as to initiate the movement of the cam levers 38, and prepare the release of the operating levers 42 before the lever 96 enters a notch and permits the removal of the knife-edge 102 from its cooperating member 103 by means of the spring 100. The effect will be that even at the greatest speed of signal transmission, the duration of the impulses is absolutely equal and uniform, resulting from the exceptional quickness of movement 35 of the contact tongue 49 from one contact point to the other and the mechanical control of this movement. The position of the cam 95 can be so adjusted in respect to that of the cams 21 that any desired degree of 40 exactness and uniformity of transmission may be obtained.

The operation of the organization of apparatus comprising the present invention, is as follows:

45 The motor 18 normally causes rotation of the main gear 15 by means of driving worm 17. Gear 15 is adapted to rotate either one of the friction disks 19 or 20. In the event that main signals are to be transmitted then friction disk 19 rotates with the main gear and friction disk 20 is prevented from rotation, and, if service signals are to be transmitted, friction disk 19 is prevented from rotation and friction disk 20 is permitted to 55 rotate.

This latter condition results in the rotation of shaft 14 and the cams 21 connected thereto. The cams 21 are so set in relation to each other that the levers 38 are depressed 60 in succession and the free end of the levers 38 removed from the ends of the operating levers 42 so that the upward movement of the latter under the action of their springs 44 is permitted, whenever one of the selecting

pins 45 enters a perforation of the tape 33, 65 the impulse controlling means.

A lever 42 whose selecting pin has entered a perforation of the tape 33, is pulled upwards by its spring 44, which, in overpowering the spring 48 of the contact lever 47, 70 causes a tilting of the latter and the transfer of the contact tongue 49 from the marking contact point 51 to the spacing contact point 50. This results in the transmission of an impulse over the line to the distant station. 75

As now well known in the art, each group of five impulses, characteristic of the Baudot code, is in some systems preceded by a start impulse. In the present apparatus this is effected by one of the levers 42, not provided with a pin rod, and therefore, not controlled by the perforated tape. 80

There are six cams on shaft 14 and a like number of cam levers and operating levers, but in a distributor employing a five unit Baudot and controlled by a perforated tape, there are only five pin rods permitting to actuate the operating levers. The sixth cam, cam lever 94 and operating lever is used not only for transmitting a start impulse, 90 but the same instrumentalities, except the cam, are also employed to transmit auxiliary signals, which arrangement is thought to be broadly new.

In the event that service signals are to be substituted for main signals, a handle 89 is pushed to the right, resulting in the removal of detent 83 from the notch 88 of disk 85 of the service signal device, permitting this disk to rotate by means of the friction disk 20, now being taken along by the main gear 15, while at the same time, the detent 82, passing into the path of rotation of the stop arm 47, prevents the rotation of shaft 14 and the operation of the associated parts of 100 the main signal transmission apparatus. 105

At the very beginning of the transmission of service signals, the bell 76 will be struck, once for each revolution of the code wheel 71, as pointed out heretofore and, as soon as handle 89 is released, the service signal means completes its cycle and is arrested by detent 83, while, at the same time, detent 82 is removed from stop arm 67, and the operation of the main signalling means resumed. 110

Referring to the release of operating levers 42, it will be noticed that the left end of cam levers 38, adapted to contact with cams 21, when rotating in the direction indicated by the arrow in Fig. 1, is peculiarly shaped, so as to form an initiating incline and then a cam lug. Cam 21 first engages the extreme end of the incline and begins to slowly depress the cam lever 38. This results in a gradual removal of the right hand ends of the cam levers 38, from the left-hand ends of the actuating levers 42. 120

The springs 44, in contracting, move the

pin rods 46 toward the tape 33 and, as soon as a cam 21 reaches the end of the incline of cam levers 38 and engages the cam lug, a quick final release of the actuating levers 42, 5 will result and the pin 45 be permitted to enter a perforation of tape 33. If such gradual release of the actuating levers 42, were not provided for, springs 44 may exert such a sudden and extended pull, that pins 45 10 may be moved with sufficient force to even perforate an unperforated portion of the tape.

What is claimed is:—

1. Apparatus for transmitting code combinations of electrical impulses comprising a single transmitting contact, actuating means for said transmitting contact, and means embodying a perforated control tape for controlling said actuating means in accordance with the code combinations to be transmitted.

2. In an apparatus for transmitting impulses, a transmitting contact, other contacts co-acting with said transmitting contact, means for actuating said transmitting contact in accordance with the impulses to be transmitted, and means for insuring engagement of said transmitting contacts with one of said other contacts during the interval allotted to each transmitted impulse.

3. A transmitter comprising contact carrying means; mechanism comprising a rotatable cam shaft for supplying operating energy to said contact carrying means and a perforated tape controlling the operation of said contact carrying means; and means controlled by the tension of said tape for stopping rotation of said cam shaft only between completed signal combinations of impulses.

4. In an automatic impulse transmitter, the combination of a single current reversing member, a plurality of tape controlled members controlling said current reversing member, and means for consecutively operating said tape controlled members whereby a perforated tape can control the position of said current reversing member.

5. Apparatus for transmitting code combinations of electrical impulses comprising a single transmitting contact, actuating means for said transmitting contact, means embodying a perforated control tape for controlling said actuating means in accordance with the code combinations to be transmitted, said actuating means comprising a plurality of members controlled in operation by said tape, and means for operating said members in successive order.

6. Apparatus for transmitting code combinations of electrical impulses comprising a single transmitting contact, actuating means for said transmitting contact, means embodying a perforated control tape for controlling said actuating means in accordance

with the code combinations to be transmitted, said actuating means comprising a plurality of members, and means for operating said members in successive order, said means comprising a rotatable cam shaft.

70

7. Apparatus for transmitting code combinations of electrical impulses comprising a single transmitting contact, actuating means for said transmitting contact, means embodying a perforated control tape for controlling said actuating means in accordance with the code combinations to be transmitted, said actuating means comprising a plurality of members controlled in operation by said tape, means for operating said members in successive order, said means comprising a rotatable cam shaft, a clutch for rotating said cam shaft, and means for driving said clutch.

75

8. Apparatus for transmitting code combinations of electrical impulses comprising a single transmitting contact, actuating means for said transmitting contact, means embodying a perforated control tape for controlling said actuating means in accordance with the code combinations to be transmitted, said actuating means comprising a plurality of members, means for operating said members in successive order, said means comprising a rotatable cam shaft and elements actuated by said cam shaft, and actuating said members.

85

9. Apparatus for transmitting code combinations of electrical impulses comprising a single transmitting contact, actuating means for said transmitting contact, means embodying a perforated control tape for controlling said actuating means in accordance with the code combinations to be transmitted, said actuating means comprising a plurality of members, means for operating said members in successive order, said means comprising a rotatable cam shaft and means for driving said perforated tape from said cam shaft.

90

10. Apparatus for transmitting code combinations of electrical impulses comprising a single transmitting contact, actuating means for said transmitting contact, means embodying a perforated control tape for controlling said actuating means in accordance with the code combinations to be transmitted, said actuating means comprising a plurality of members, means for operating said members in successive order, said means comprising a rotatable cam shaft, means for driving said perforated tape from said cam shaft, said means for driving the tape comprising a step by step advancing mechanism for the tape, actuated to advance the tape only between the transmission of completed code combinations of impulses.

105

11. Apparatus for transmitting code combinations of electrical impulses comprising a single transmitting contact, actuating means for said transmitting contact, means

115

120

125

130

- embodiment a perforated control tape for controlling said actuating means in accordance with the code combinations to be transmitted, said actuating means comprising a plurality of members, means for operating said members in successive order, said means comprising a rotatable cam shaft, means for driving said tape comprising a step by step advancing mechanism for the tape, actuated to advance the tape only between the transmission of completed code combinations of impulses; and a special cam on said cam shaft for operating said step by step mechanism.
12. Apparatus for transmitting code combinations of electrical impulses comprising a single transmitting contact, actuating means for said transmitting contact, means embodying a perforated control tape for controlling said actuating means in accordance with the code combinations to be transmitted, and means for preceding each code combination of impulses with a fixed and invariable impulse.
13. Apparatus for transmitting code combinations of electrical impulses comprising a single transmitting contact, actuating means for said transmitting contact, means embodying a perforated control tape for controlling said actuating means in accordance with the code combinations to be transmitted, means for preceding each code combination of impulses with a fixed and invariable impulse, said last mentioned means being independent of said perforated tape control.
14. Apparatus for transmitting code combinations of electrical impulses comprising a rotatable cam, a single transmitting contact, actuating means for said transmitting contact, means embodying a perforated control tape for controlling said actuating means in accordance with the code combinations to be transmitted, means for preceding each code combination of impulses with a fixed and invariable impulse, said last mentioned means being independent of said perforated tape control, and comprising an actuating member for said single contact operated by said rotatable cam.
15. Apparatus for transmitting code combinations of electrical impulses comprising a single transmitting contact, actuating means for said transmitting contact, means embodying a perforated control tape for controlling said actuating means in accordance with the code combinations to be transmitted, and auxiliary automatic means for operating said single contact independently of said tape control, to transmit code combinations of impulses.
16. Apparatus for transmitting code combinations of electrical impulses comprising a single transmitting contact, actuating means for said transmitting contact, means embodying a perforated control tape for controlling said actuating means in accordance with the code combinations to be transmitted, auxiliary automatic means for operating said single contact independently of said tape control, to transmit code combinations of impulses and means for interrupting operation of said tape control means during the period when said auxiliary automatic means is operating.
17. Apparatus for transmitting code combinations of electrical impulses comprising a single transmitting contact, actuating means for said transmitting contact, means embodying a perforated control tape for controlling said actuating means in accordance with the code combinations to be transmitted, auxiliary automatic means for operating said single contact independently of said tape control, to transmit code combinations of impulses and means for interrupting the operation of said auxiliary automatic means when said tape control means is in operation.
18. In an apparatus for transmitting impulses, a transmitting contact, other contacts co-acting with said transmitting contact, means for actuating said transmitting contact in accordance with the impulses to be transmitted, means for insuring engagement of said transmitting contact with one of said other contacts during the interval allotted to each transmitted impulse, said last mentioned means comprising a locking member for locking said transmitting contact in actuated position.
19. In an apparatus for transmitting impulses, a transmitting contact, other contacts co-acting with said transmitting contact, means for actuating said transmitting contact in accordance with the impulses to be transmitted, means for insuring engagement of said transmitting contacts with one of said other contacts during the interval allotted to each transmitted impulse, said last mentioned means comprising a locking member for locking said transmitting contact in actuated position, said locking member being adapted to assist movement of said transmitting contact.
20. In an apparatus for transmitting impulses, a rotatable cam, a transmitting contact, other contacts co-acting with said transmitting contact, means for actuating said transmitting contact in accordance with the impulses to be transmitted, means for insuring engagement of said transmitting contacts with one of said other contacts during the interval allotted to each transmitted impulse, said last mentioned means comprising a locking member for locking said transmitting contact in actuated position, said locking member being adapted to assist movement of said transmitting contact, and controlled by said rotatable cam driven in timed relation with the transmission of impulses.
21. In an apparatus for transmitting im-

- 6 pulses, actuating springs, a transmitting contact, other contacts co-acting with said transmitting contact, means for actuating said transmitting contact in accordance with the impulses to be transmitted, means for insuring engagement of said transmitting contacts with one of said other contacts during the interval allotted to each transmitted impulse, said last mentioned means comprising a locking member for locking said transmitting contact in actuated position, said locking member being adapted to assist movement of said transmitting contact controlled by a rotatable cam driven in timed relation with the transmission of impulses and actuated in its locking and unlocking movement by energy stored in said actuating springs.
22. Apparatus for transmitting code combinations of electrical impulses comprising a single transmitting contact, springs associated with said contact, actuating means for said transmitting contact, means embodying a perforated control tape for controlling said actuating means in accordance with the code combinations to be transmitted, said transmitting contact being actuated solely by energy stored in said springs.
23. Apparatus for transmitting code combinations of electrical impulses comprising spring members, a single transmitting contact, actuating means for said transmitting contact, means embodying a perforated control tape for controlling said actuating means in accordance with the code combinations to be transmitted, said actuating means comprising a plurality of members, means for operating said members in successive order, each of said members being actuated solely by energy stored in said springs.
24. Apparatus for transmitting code combinations of electrical impulses comprising a single transmitting contact, actuating means for said transmitting contact, means embodying a perforated control tape for controlling said actuating means in accordance with the code combinations to be transmitted, and means controlled by the tension of said control tape for stopping transmission only between completed combinations of impulses.
25. A transmitter comprising contact carrying means; mechanism comprising a rotatable cam shaft for supplying operating energy to said contact carrying means, a perforated tape controlling the operation of said contact carrying means, and means controlled by the tension of said tape for stopping rotation of said cam shaft only between completed signal combinations of impulses, said last mentioned means comprising a stop member adapted to be interposed in the path of a stop projection carried by said cam shaft.
26. A transmitter comprising contact carrying means, mechanism comprising a rotatable cam shaft for supplying operating energy to said contact carrying means, a perforated tape controlling the operation of said contact carrying means, a tape actuated lever, a spring connection, and means controlled by the tension of said tape for stopping rotation of said cam shaft only between completed signal combinations of impulses, said last mentioned means comprising a stop member adapted to be interposed in the path of a stop projection carried by said cam shaft, said stop member being actuated by means of said tape actuated lever and spring connection.
27. In an automatic impulse transmitter, the combination of a single current reversing member, a plurality of controlled members controlling said current reversing member, and means, including a perforated tape, for consecutively operating said controlled members for controlling the position of said current reversing member.
28. An automatic impulse transmitter comprising mechanically operated means, a plurality of members normally retracted by said mechanically operated means, a tape for controlling said members a single transmitting contact, and means operable by said members whereby said transmitting contact is actuated in accordance with perforations in the tape.
29. An automatic impulse transmitter comprising a single transmitting contact, a plurality of members regulating the actuation of said contact, a tape for controlling said members, mechanically operated means for controlling the successive actuation of said contact in accordance with the position of the members, and means for operating said contact invariably at the commencement of each signal period.
30. An automatic impulse transmitter comprising a single transmitting contact, a plurality of members regulating the actuation of said contact, a tape for controlling said members, mechanically operated means consequently releasing said members to actuate said contact, and means for operating said contact invariably at the commencement and close of each signal period.
31. An automatic impulse transmitter comprising a single transmitting contact, a plurality of members controlling the actuation of said contact, a tape for controlling said members, mechanically operated means for releasing said members for actuating said contact, a lever, and a cam acting on said lever for operating said contact invariably at the commencement and close of each signal period.
32. In an automatic tape transmitter, a perforated tape, a single transmitting contact, means for actuating said contact in accordance with perforations in said tape.

and means under the control of the tape for automatically starting the transmitter.

33. In an automatic tape transmitter, a perforated tape, a single transmitting contact, means for actuating said contact in accordance with perforations in said tape, and means under the control of the tape for automatically stopping the transmitter.

34. In an automatic tape transmitter, a perforated tape, a single transmitting contact, means for actuating said contact in accordance with the perforations in said tape and mechanically operated means under the control of the tape for automatically starting and stopping the transmitter.

35. In combination, a perforated tape, a single transmitting contact, mechanically operated means for actuating said contact in accordance with the perforations in said tape, and a tape lever operated by the tension of the tape to mechanically stop the transmitter.

36. In combination, a perforated tape, a single transmitting contact, mechanically operated means for actuating said contact in accordance with the perforations in said tape, and a tape lever controlled by the tension of the tape to mechanically start the transmitter.

37. In combination, a perforated tape, a single transmitting contact, mechanically operated means for actuating said contact in accordance with the perforations in said tape, and a tape lever controlled by the tension of the tape to mechanically start and stop the transmitter.

38. In combination, a perforated tape, a single transmitting contact, mechanically operated means for actuating said contact in accordance with the perforations in said tape, and means operated solely through the instrumentalities of mechanical movements for automatically stopping and starting the transmitter.

39. An automatic tape transmitter comprising a single transmitting contact, a plurality of tape controlled members for controlling the actuation of said contact, and spring means for elevating said tape controlled members when a perforation is brought into alignment therewith for causing the corresponding actuation of the contact.

40. An automatic tape transmitter comprising a single transmitting contact, a plurality of tape controlled members for controlling the actuation of said contact, and mechanically operated means for elevating said tape controlled members when a perforation is brought into alignment therewith for causing the corresponding actuation of the contact.

41. In an automatic impulse transmitter, a single transmitting contact, a plurality of fingers for controlling the actuation of said

contact, an operating member individual to each of said fingers, a rotating shaft, a plurality of cams secured to said shaft, one for each of said operating members and arranged to operate said members in succession whereby said contact is actuated in accordance with the position of said fingers.

42. In an automatic impulse, a perforated tape, a single transmitting contact, a plurality of fingers for controlling the actuation of said contact, an operating member individual to each of said fingers, a rotating shaft, a plurality of cams secured to said shaft, one for each of said operating members and arranged to operate said members in succession whereby said contact is to be actuated in accordance with the position of said fingers, and means under the control of said shaft for automatically stopping the rotation of said cams.

43. In a telegraph transmitter, a perforated tape, a finger therefor, means normally urging said finger into engagement with said tape, and means for preventing said finger from perforating said tape while being brought into engagement therewith.

44. In a telegraph transmitter, a perforated tape, a finger therefor urged into engagement with said tape, and means for controlling the force with which said finger engages said tape.

45. In a telegraph transmitter, a perforated tape, a finger therefor, means for urging said finger into engagement with said tape, and means for controlling the release of said last mentioned means.

46. A transmitter comprising a perforated tape, a contact carrying means controlled by said perforated tape, a plurality of cam members for sequentially releasing said contact carrying means for control by said perforated tape, said cam members being so designed as to first gradually and then very suddenly release said contact carrying means.

47. In a transmitter, a perforated tape, a plurality of fingers arranged to move into the perforations of said tape, said fingers being held normally out of engagement with said tape, a plurality of cam members for sequentially releasing said fingers to engage said tape, said cam members being so arranged as to first gradually release said fingers and then suddenly completely release said fingers.

48. In a telegraph transmitter, a perforated tape, a finger normally held out of engagement with said tape, means for gradually permitting said fingers to move into engagement with said tape, and means operative after said finger has come into engagement with said tape for completely releasing said finger to enter the perforations in said tape.

49. In a telegraph transmitter, comprising

- 5 a perforated tape and fingers therefor, the method of operating said finger which comprises bringing the finger gradually into engagement with the tape and after the engagement suddenly releasing the finger to permit it to move into a perforation. 70
- 10 50. In a telegraph transmitter, a perforated tape, a finger therefor, said finger being normally locked out of engagement with said tape, means urging said finger into engagement with said tape, and means for gradually releasing said finger until it engages said tape, said means thereafter completely releasing said finger. 75
- 15 51. In a telegraph transmitter, contact carrying means, means for operating said contact carrying means, and means for thereafter latching said contact carrying means in operative position. 80
- 20 52. In a telegraph transmitter, a contact carrying means having a plurality of positions, means for selectively operating said contact carrying means to either of its positions, means for thereafter latching said contact carrying means in operated position, said means being also operative to release said contact carrying means from its operated position. 85
- 25 53. In a telegraph transmitter, contact carrying means, means for selectively operating said contact carrying means, and second means for controlling the length of time during which the contact carrying means is held in its operated position. 90
- 30 54. In a telegraph transmitter, contact carrying means, a perforated tape for operating said contact carrying means, and means for controlling the length of time during which said contact carrying means 95
- 35 remain in the position operated by said perforated tape. 100
- 40 55. In a telegraph transmitter, a contact carrying means, and means including a perforated tape for controlling said contact carrying means to transmit code combinations of impulses which are of a predetermined length. 105
- 45 56. In a telegraph transmitter, a perforated tape, a single contact controlled by said perforated tape to transmit code combinations of impulses, and means for controlling the length of said impulses. 110
- 50 57. In a telegraph transmitter, contact carrying means, a perforated tape for operating said contact carrying means, and means released for operation following the operation of said contact carrying means under control of said perforated tape for preventing chattering of said contact carrying means in operated position. 115
- 55 58. In a telegraph transmitter, a perforated tape, contact carrying means, a plurality of cam members, means sequentially released by said cam members for operating said contact member under control of said 120
- 60 tape and a second means including cam members released in timed relation with said first mentioned means for positively operating said contact carrying means in position. 125
59. In a telegraph device, members having a plurality of positions selectively operated, and means released for operation in timed relation with the selective operation of said first mentioned member for positively moving said member in operated position. 75
60. In a telegraph device, a member having a plurality of positions, means for selectively operating said member to said positions, and means for maintaining said member in said operated position for a predetermined length of time. 80
61. In a telegraph device, a member having a plurality of positions, means including cam members for operating said member to either of its positions, and means including other cam members for latching said member in operated position. 85
62. In a telegraph device, a member having a plurality of positions, means including cam members for operating said member to either of its positions, and second means including other cam members for determining the length of time said member will remain in operated position. 90
63. In a telegraph transmitter, contact carrying means, a perforated tape for operating said contact carrying means to transmit a code combination of impulses and additional means for transmitting an impulse of a pre-determined character at the beginning and at the end of each code combination. 95
64. In a telegraph transmitter, contact carrying means for transmitting code combinations of impulses, a perforated tape, cam members co-operating with said perforated tape for operating said contact carrying and additional cam members for controlling said contact carrying means to transmit an impulse of a pre-determined character at the beginning and at the end of each code combination. 100
65. In a telegraph transmitter, a contact carrying means, cam members and a perforated tape, said contact carrying means being operated by the perforations in said tape and under control of said cam members or directly by said cam members. 105
66. In a telegraph transmitter, a single contact member, a perforated tape, and means operable under control of the perforations in the tape for directly operating said contact carrying means. 110
67. In a telegraph transmitter, single contact means for transmitting impulses, a perforated tape, and means operated by the perforation in the tape for directly operating said impulse transmitting means. 115

68. In a telegraph transmitter, contact carrying means, a perforated tape, locked means under control of the perforations in said tape for operating said contact carrying means, and second means for releasing said first mentioned means to be operated by said perforated tape. 70
69. In a telegraph transmitter, contact carrying means, a perforated tape, normally locked means under control of the perforations in said tape for operating said contact carrying means, and cam members for releasing said first mentioned means to be operated by said perforated tape. 75
70. A transmitter comprising a common contact tongue; a plurality of members operable to actuate said tongue, a perforated tape controlling the operation of said members, and spring actuated means applying the entire operating energy to said members. 80
71. A transmitter comprising a plurality of contact operating members, a perforated tape controlling the operation of said members in accordance with signals to be transmitted, a rotatable cam shaft for causing successive operation of said members, and a stop for said cam shaft operable by the tension of said tape. 85
72. A transmitter comprising a plurality of contact operating members; contact carrying means operated by said operating members; a perforated tape controlling the operation of said members in accordance with the code combinations of selecting conditions to be transmitted; actuating means for said members; auxiliary means adapted to operate said series of code combinations, and a common driving means for said actuating means and said auxiliary means. 90
73. A transmitter comprising a single transmitting contact; means for actuating said contact to transmit code combinations of electrical impulses, and auxiliary signalling means adapted to actuate said contact in accordance with a predetermined series of signals. 95
74. In a telegraph transmitter, a contact carrying means, means for operating said contact carrying means to transmit a code combination of impulses, and auxiliary means for operating said contact carrying means, and manually operated means for simultaneously rendering one of said means non-operative and the other operative. 100
75. In a telegraph transmitter, contact carrying means, a first means for controlling the operation of said contact carrying means, a second means for controlling the operation of said contact carrying means, and means for putting said contact carrying means under control of either of said operating means. 105
76. In a telegraph transmitter, contact carrying means, a first means for controlling the operation of said contact carrying means, a second means for controlling the operation of said contact carrying means, and cam members for operating said contact carrying means, second rotating cam members for controlling the operation of said contact carrying means, and means for putting said contact carrying means under control of either of said operating means. 110
77. In a telegraph transmitter, contact carrying means, means for operating said contact carrying means, second means for operating said contact carrying means, said second means being normally latched out of operation, and means for simultaneously unlatching said second means and latching said first means. 115
78. In a telegraph transmitter, contact carrying means, cam members for operating said contact carrying means, second rotating cam members for operating said contact carrying means and means for placing said contact carrying means under control of either of said cam members. 120
79. In a telegraph transmitter, contact carrying means, a plurality of rotating cam members for controlling the operation of said contact carrying means, second rotating cam members for controlling the operation of said contact carrying means, said second contact carrying means being normally latched out of operation and means for simultaneously releasing said second means and latching said first mentioned means. 125
80. In a telegraph transmitter, contact carrying means, a plurality of rotating cam members for controlling the operation of said contact carrying means, second rotating cam members for controlling the operation of said contact carrying means, said second contact carrying means being normally latched out of operation and manually operated means for simultaneously releasing said second means and latching said first mentioned means. 130

83. In a telegraph transmitter, contact carrying means, rotating cam members for controlling the operation of said contact carrying means, said second cam members being normally latched against operation, and means for releasing said second cam members for operation, said means being also operative to latch said first mentioned means against operation at a predetermined position in its rotation, said means being also operative when restored to again latch said second cam members. 70
84. In a telegraph transmitter, contact carrying means, rotating cam members for controlling the operation of said contact carrying means, second rotating cam members for controlling the operation of said contact carrying means, said second cam members being normally latched against operation, and means for releasing said second cam members for operation, said means being also operative to latch said first mentioned means against operation at a pre-determined position in its rotation, said means being also operative when restored to again latch said second cam members at a pre-determined position. 75
85. In a telegraph transmitter, contact carrying means, rotating cam members for controlling the operation of said contact carrying means, second rotating cam members for controlling the operation of said contact carrying means, said second cam members being normally latched against operation, and means for releasing said second cam members for operation, said means being also operative to latch said first mentioned means against operation at a pre-determined position in its rotation, said means being also operative when restored to again latch said second cam members invariably at a pre-determined position. 80
86. In a telegraph transmitter, a rotating cam shaft, second rotating cam shaft, contact carrying means operable under control of either of said cam shafts, and means whereby said control is switched only at a pre-determined position in the rotation of either of said cam shafts. 85
87. In a telegraph transmitter, a contact carrying means, means for controlling the operation of said contact carrying means to transmit a code combination of impulses, second means for controlling the operation of said contact carrying means to transmit a code combination of impulses, and means for switching the control of said contact carrying means to either of said control means, said last mentioned means being effective to perform said switching operation only at the end of the transmission of a code combination of impulses. 90
88. In a telegraph transmitter, contact carrying means, a plurality of means for controlling the operation of said contact carrying means to transmit code combinations of impulses, and means for switching the control of said contact carrying means to any of said control means, said switching means being effective only at the conclusion of the transmission of a code combination of impulses. 95
89. In a telegraph transmitter, contact carrying means, a perforated tape, rotating cam members, means operated by the perforations in said tape under control of said rotating cam members for operating said contact carrying means, second cam members for controlling the operation of said contact carrying means independent of said tape, and means for switching said control to either of said rotating cam members. 100
90. In a telegraph transmitter, contact carrying means, a perforated tape, rotating cam members, means operated by the perforation in said tape under control of said rotating cam members for operating said contact carrying means, second cam members for controlling the operation of said contact carrying means independent of said tape, and means for simultaneously rendering one of said rotating cam members non-operative and starting the other into operation. 105
91. In a telegraph transmitter, a tape comprising perforations of various combinations arranged transversely with respect to said tape and a single contact transmitter controlled by said perforation for transmitting code combinations of impulses in accordance with said perforations. 110
92. In a telegraph transmitter, a perforated tape, and a single contact transmitter for transmitting code combinations of impulses in accordance with the perforations of said tape for each position of said tape. 115
93. In a telegraph transmitter, a perforated tape, a single contact transmitter controlled by the perforations of said tape for transmitting code combinations of impulses while said tape is held stationary. 120
94. In a telegraph transmitter, a perforated tape, a single contact, means for sequentially placing said contact under control of the succeeding perforations of said tape while the tape is held stationary, and means operative following the transmission of said code for stepping said tape to a succeeding code combination of perforations. 125
95. In a telegraph transmitter, a tape, perforated in code combinations, a single contact transmitter, cam members for sequentially placing said contact under control of said perforations while said tape is held stationary, and a cam member operative following the operation of all the perforations of the code for stepping said tape to the next set of code combinations. 130
96. In a telegraph transmitter, a tape provided with perforations transversely with

- respect to said tape, a single contact transmitter, cam operated means for sequentially placing said contact transmitter under control of said perforations while said tape is held stationary, and a cam member operative following the transmission of the code for stepping said tape to a succeeding code combination of perforations.
97. In a transmitter for telegraph systems, in which the signals each comprise a start impulse followed by a definite number of selecting impulses, a set of tape-controlled selectors, a rotary member, motor-driven clutch means for continuously advancing said member during each signal period, means mechanically actuated by said member for feeding the tape and for moving said selectors to and from the tape, contact means operated under the sole mechanical control of said actuating member for imparting the start impulses and under the joint mechanical control of said member and said selectors for transmitting the selecting impulses, and a tape-controlled stop operable to arrest said rotatable member only between completed signals.
98. In a telegraph transmitting apparatus, transmitting contact means, a rotary, mechanically acting cam member adapted by its rotary movement to effect the operation of said contact means and thereby transmit a start impulse followed by a definite number of selecting impulses during each signal period, a set of tape-controlled, mechanically acting selectors for varying the selecting impulses and a mechanically acting, tape-controlled stop device operable to arrest said rotary cam member only between completed signals.
99. In apparatus for transmitting code combinations of impulses, impulse transmitting contacts, a set of impulse selectors, a rotary contact actuating member cooperating with said selectors to transmit the selected impulses, a second rotary contact actuating member for determining the lengths of the transmitted impulses, and means for continuously advancing said rotary actuating members in definite relation during each signal period.
100. In a telegraph transmitter having cam-actuated transmitting contacts, a set of impulse selectors, a rotary, actuating cam member successively cooperating with said selectors to effect the transmission of selected impulses, a second rotary actuating cam member for determining the lengths of the transmitted impulses and a drive shaft for continuously advancing said actuating cam members in definite relation during each signal period.
101. In telegraph apparatus for transmitting code combinations of impulses, contact actuating means comprising a motor driven shaft, a set of successively acting cam sections on said shaft, a corresponding set of contact actuating members individual to said cam sections and successively actuated thereby to effect the transmission of selected impulses, a second set of cam sections on said shaft and a common member actuated thereby for determining the lengths of the transmitted impulses.
102. In a telegraph transmitter having mechanically actuated contacts for transmitting code combinations of impulses, a set of tape-controlled impulse selectors, a rotary contact actuating member cooperating with said selectors, an auxiliary contact actuating member for transmitting a code combination of impulses independently of said selectors and interlocking means between said actuators to prevent the simultaneous operation thereof.
103. In a telegraph transmitter having cam actuated transmitter contacts for transmitting code combinations of impulses, a set of tape-controlled impulse selectors, a rotary contact actuating cam member cooperating with said selectors, an auxiliary rotary contact actuating cam member for transmitting a code combination of impulses independently of said selectors, and wholly mechanical start-stop interlocking means interposed between said actuators for preventing the simultaneous operation thereof and operable to initiate and arrest the same only between completed signals.

Signed at Brooklyn, in the county of Kings and State of New York, this first day of October, 1921.

EDWARD E. KLEINSCHMIDT.
